UNITED STATES PATENT OFFICE.

LUDWIG KÜHN, OF CHARLOTTENBURG, NEAR BERLIN, REPUBLIC OF GERMANY, AS-SIGNOR TO WESTINGHOUSE ELECTRIC AND MANUFACTURING COMPANY, OF EAST PITTSBURGH, PENNSYLVANIA, A CORPORATION OF PENNSYLVANIA.

SENDING SYSTEM.

Application filed September 3, 1921. Serial No. 498,566.

(GRANTED UNDER THE PROVISIONS OF THE ACT OF MARCH 3, 1921, 41 STAT. L., 1313.)

- This invention relates to sending devices for either telegraphic or telephonic radio communication.
- It is an object of this invention to avoid the disadvantages which frequently accompany the regenerative action of transmitters in which the plate circuit is electrostatically or electromagnetically coupled to the grid circuit.
- 10 It is a further object of this invention to provide for modifying the amplitude of continuous high frequency oscillations in the grid circuit, without employing energy obtained from the plate circuit.
- 15 It is a further object of this invention to provide a tuned circuit, resonant at high frequency, with a device by means of which a low frequency modulation may be impressed thereon.
- 20 It is a further object of this invention to provide a modulating means which employs only a very small amount of energy and is capable of producing large changes in the radiated energy.
- 25 Other objects of my invention and details of the construction of the device will be apparent from the following description and the accompanying drawing in which:
- Figure 1 is a diagram of circuits showing one form of my invention,
- 30 Fig. 1^a is a diagrammatic illustration of a modification of one part of the device shown in Fig. 1,
- Fig. 1^b is a like illustration of another modification of the same part, and
- 35 Fig. 2 is a diagrammatic showing of circuits embodying another modification of my invention.
- The vacuum tube device is provided with an anode 1 and a cathode 2. A battery 3 and a resistance 4 constituting the usual arrangement for supplying heating current to the filament or cathode 2.
- 40 The plate circuit, which connects the anode 1 and cathode 2, includes an inductance 6 by which it is coupled to the radiated circuit including an antenna 5 and the ground connection. The plate circuit is supplied with energy by a battery 7 which is shunted by a condenser 8 in the usual way.
- 45 The plate circuit is supplied with a grid 9 which is connected to a circuit 10, tuned
- to a high-frequency resonance by means of the inductance 12 and adjustable condenser 11. A coil 13, of comparatively small inductance, is included in series in the circuit 10. The circuit 10 is supplied with high frequency energy in any desired way. For example, a coil 12' connected to any source of high-frequency energy may be placed in 55 inductive relation with the coil 12.
- 50 Various means may be used for impressing low frequency potential changes upon the coil 13. One way of doing this is illustrated in Fig. 1, in which the terminals 14 and 15 of this coil are connected through a battery 16 and a microphone 17.
- 55 When sound is received on the microphone, current fluctuations are developed in the circuit 16-13 which causes a difference 60 of potential between the terminals of this coil and this potential difference is superposed upon the potential difference due to the high-frequency oscillations in the circuit 10, both high-frequency and low-frequency 65 changes being impressed upon the grid 9. The energy of the high-frequency oscillations in the circuit 10 may, if desired, be relied upon to supply the current through the microphone 17, and the battery 16 70 omitted.
- 75 The potential changes impressed upon the grid 9 are amplified by the tube 1 and appear in the antenna circuit as modulated, high-frequency oscillations. Since there is no 80 coupling between the grid circuit 14 and the plate circuit, no feed-back action takes place. It is not possible, therefore, for the tube to obliterate the signals by oscillations generated by the tube itself. Since there is no 85 coupling to adjust, it is not possible to distort the signal by too close a coupling. The potential changes at the terminals of the coil 13, need not be produced by a microphone. Any desired way of introducing an 90 audio-frequency variation may be substituted. In Fig. 1^a a buzzer is shown instead of the microphone. The buzzer is provided with any desired means for regulating the frequency of the armature and the pitch of 95 the modulation in the radiated signalling energy will be adjusted by thus regulating the buzzer frequency.
- 100 In Figure 1^b, a small alternating current

generator is shown for impressing upon the coil 13, an audio frequency variation. Since the energy needed for this modulation is small, the alternating current generator may 5 be driven by a small siren.

Instead of coil 13, a condenser may be used. This is illustrated in Fig. 2 in which the resonant circuit 10 is tuned by means of the inductance 12 and the adjustable condenser 11 and is energized from the coil 12' or in any other desired way. The condenser 20 is inserted in the circuit 10 in a position corresponding to that of the coil 13. A second condenser 19 is shown between the grid 15 9 and the connected point of the circuit 10. Either of the condensers 19 and 20 may be omitted if desired. In order to provide an all-metallic path between the grid 9 and the cathode 2, the connection by means of which 20 20 the audio-frequency energy is supplied is joined to the high-frequency circuit at the grid side of the condenser 19 and the cathode side of the condenser 20. In this connection, the secondary of a transformer 18 is included. 25 25 The primary of this transformer is supplied with audio-frequency energy in any desired way; for example, by any of the means described in connection with Fig. 1.

The condensers 19 and 20 are too small to 30 pass audio-frequency current but are large enough to permit the radio-frequency current to pass readily. Consequently, the audio-frequency potential difference upon opposite sides of the condensers 19 and 20 35 is impressed upon the grid 9 without interfering with the action of the high-frequency circuit 10. In the same way, the secondary of the audio-frequency transformer 18 acts as a choke coil, preventing passage of the 40 high-frequency oscillations, but conducting audio-frequency currents. The circuit 10, therefore, is not disturbed by the potentials on the condenser 20, but is tuned by means of the adjustable condenser 11 and carries 45 continuous high-frequency oscillations which are impressed, through the condenser 19, upon the grid 9. The grid 9, therefore, carries both frequencies.

The action of the righthand half of the

device illustrated in Fig. 2 is like that described in connection with Fig. 1, amplifying the energy impressed upon the grid 9 and sending out high-frequency radiations, modulated at an audio frequency. The absence of any coupling between the anode 55 circuit and the grid circuit is as complete in the form illustrated in Fig. 2 as it is in the form illustrated in Fig. 1 and the resulting advantages are the same.

Although I have illustrated and specifically described but a few modifications of my device, other variations will be apparent to those skilled in the art and the limited number of forms specifically described is not to be regarded as a limitation. No limitation 65 except that necessitated by the prior art or indicated by the claims is intended.

I claim as my invention:

1. In a non-regenerative, vacuum-tube amplifier including a grid, a filament and 70 a plate, a grid circuit including a source of radio-frequency and a tuning device co-operating therewith to render said grid circuit resonant to said radio frequency, an all-metallic connection between the grid and 75 filament for removing grid charge and stopping condensers on each side of said source of radio frequency preventing the grid charge from passing through said source of radio frequency. 80

2. In a non-regenerative, vacuum-tube amplifier including a grid, a filament and a plate, a grid circuit including a source of radio-frequency and a tuning device co-operating therewith to render said grid circuit 85 resonant to said radio frequency, an all-metallic connection between the grid and filament for removing grid charge, said all-metallic connection including a source of audio frequency and stopping condensers on 90 each side of said source of radio frequency preventing the grid charge from passing through said source of radio frequency, said source of audio frequency together with said stopping condensers presenting a high impedance to the radio frequency. 95

In testimony whereof I affix my signature.

DR. IG. LUDWIG KÜHN.
